(57) **CLAIM**

The ornamental design for an interconnectable module for a tree surround, as shown and described.

DESCRIPTION

FIG. 1 is a perspective view of an interconnectable module for a tree surround showing my new design, the additional modules that form the complete surround being shown in broken line form are for illustrative purposes only and form no part of the claimed design.

FIG. 2 is a top plan view of the interconnectable module of FIG. 1;

FIG. 3 is an inside elevational view thereof;

FIG. 4 is an outside elevational view thereof;

FIG. 5 is a first end elevational view thereof;

FIG. 6 is a second end elevational view thereof; and,

FIG. 7 is a bottom plan view thereof.
